UNITED STATES PATENT OFFICE.

ASA L. SAWYER, OF EAST PROVIDENCE, RHODE ISLAND, ASSIGNOR TO HALLAM-RICE CO., A COPARTNERSHIP CONSISTING OF WALTER E. HALLAM AND HENRY W. RICE, OF PAWTUCKET, RHODE ISLAND.

CLASP-PIN.

1,258,258.

Specification of Letters Patent.

Patented Mar. 5, 1918.

Application filed December 7, 1916. Serial No. 135,545.

To all whom it may concern:

Be it known that I, ASA L. SAWYER, a citizen of the United States, and resident of East Providence, R. I., have invented certain new and useful Improvements in Clasp-Pins, of which the following is a specification.

This invention relates to clasp pins and is more particularly intended for use in connection with that type of pin known as lingerie pins which are commonly employed to hold in place the shoulder straps of underwear or other garments, although said invention is applicable to other types of pin as well.

One of the objects of the invention is to provide a pin of this class that shall be reliable and certain in its action and be so constructed as to prevent the accidental opening of the clasp when in use and also to minimize the tendency of the lace or other straps to catch against and be torn by the sharp edges of the pin. The invention consists in a construction whereby a perfumery or scent pad is attached to said pin without in any way interfering with its efficient performance of its normal functions.

These and other features of the invention will be particularly described in this specification and will be defined in the claims here-to annexed.

In the accompanying drawings I have illustrated the preferred mode of embodying the principles of this invention in which, Figure 1 is a side elevation showing the complete pin in its normal position of use on the shoulder outlined in dotted lines.

Fig. 2 is an enlarged plan view thereof.

Fig. 3 is a side elevation showing the retaining means for the pad holder.

Fig. 4 is a plan view of the pad retaining device or holder.

Fig. 5 is a side elevation thereof.

Fig. 6 is an end elevation thereof.

Fig. 7 is an enlarged view of the complete device assembled showing a central section through the pad and its holder.

In the practice of my invention according to the form illustrated in the drawings the pin proper is shown as consisting of a single piece of appropriate sheet metal bent to form two approximately parallel arms a , b , provided at their free ends respectively with reversely bent or curved hook-like members a' b' , which are so arranged in relation to

each other that the hook b' is capable of being forced over the exterior of the hook a' into mutually interlocking position.

I prefer to make these hook members of concavo-convex cross-section partly because I find that this construction makes a more reliable interlocking connection with less liability to accidental opening or springing apart and partly because it prevents any lateral movement of the interlocked arms with relation to each other and also because such curvature tends to prevent the lace shoulder strap from catching upon the thin edge of the hook when in use so as to lessen the tendency of bunching or tearing.

In order to enable the pin to carry a perfumery or scent pad I provide a pad holder which in this case comprises a strip of thin sheet metal c having its lateral edges upset to form flanges c^2 which may be intersected at intervals by notches to allow the circulation of air through the holder in contact with the pad d which is made of absorbent cotton, felt or other suitable material. The opposite ends of the holder c are bent down to form projecting flanges c^3 which are preferably notched at their middle portions as shown at c^4 in order to receive co-operating tongues a^2 which are preferably struck up from the under arm or member a of the pin in position to pass through said notches and have their ends preferably extended into small holes c^5 formed in each end of the wall of the holder.

The sloping end walls of the holder c and the sloping tongues a^2 with their ends projecting into the interior of the holder present a smooth inclined surface which affords no sharp edge or shoulder against which the lace shoulder straps can catch when being inserted within the pin.

It will be observed that the lower or under member a of the pin is concave so as to better remain in proper position on the shoulder and also to give a certain resiliency or spring to facilitate the opening and closing of the pin and also for tightening the interlocking engagement of the pin under the pressure exerted thereon by the straps passing between the two members. The upper face of the holder c is provided with an aperture c' to allow the escape of the scent fumes while the notches in the side flanges c^2 not only aid in maintaining the circulation of air through the pad but also

serve to give the scent pad itself an appreciable degree of flexibility.

As the pad holder *c* is a separate flexible member mechanically attached at its two ends to the curved arm of the pin it does not interfere with the proper bending or placing of the pin and yet by being placed on the lower member of the pin it is less likely to obstruct the insertion of the straps for which the pin is intended and also receives a greater amount of heat from the body which increases the diffusion of the perfumery. With the structure shown not only is the efficiency and reliability of the pin not diminished by the application of the scent pad holder but there is also the further advantage that the holder may be readily removed and replaced when desired.

What I claim is:

- 20 1. A clasp pin embracing in combination two coöperating arms having their free ends formed to have interlocking but detachable engagement with each other, a pad holding member and means for securing said pad holding member to the inside face of one of said arms while leaving the arm free to bend or yield transversely to its length, substantially as described.
- 25 2. A clasp pin comprising a pair of coöperating members having their free ends bent to form coöperative hook members each having a concavo-convex cross section whereby lateral movement of said arms in relation to each other is prevented when they are interlocked, one of said arms being longitudinally curved, substantially as described.
- 30 3. A clasp pin embracing in its construction a spring metal strip bent to form two approximately parallel arms whose free ends are formed with means for interlockingly engaging each other, one of said arms being provided with retaining members pro-

jecting from its inside face and a pad holding member arranged on the inside face of 45 said arm to be engaged by said retaining means, substantially as described.

4. A clasp pin embracing in its construction two longitudinal coöperating arms having their free ends formed to be detachably interlocked with each other and a pad holding member to be detachably secured to one of said arms, substantially as described.

5. A clasp pin embracing in combination two coöperating arms whose free ends are formed to interlockingly engage each other, one of said arms being curved inwardly toward the other in a longitudinal direction, a pad holding member, and means for securing said pad holding member upon said 60 curved arm while permitting said curved arm to flex under strain in a transverse direction, substantially as described.

6. A clasp pin embracing in its construction two coöperating arms whose free ends are formed to detachably interlock with each other, a pad holding member embracing a perforated plate formed to receive a scent pad, one of said arms being provided with projecting tongues to engage coöordinated 70 notches and apertures in the pad holding member in order to detachably hold said pad holding member to said arm, substantially as described.

7. A clasp pin embracing in its construction two longitudinal arms whose free ends are formed to interlockingly engage each other, the lower arm being bowed inwardly toward the other arm, a scent pad holder detachably secured to the convex curved arm 80 by connections permitting said arm to be flexed under transverse strain, substantially as described.

In witness whereof, I have subscribed the above specification.

ASA L. SAWYER.
